UNITED STATES PATENT OFFICE.

JOHN H. OWENS, OF RACINE, WISCONSIN.

TRAP OR CLEAN-OUT COVER.

1,413,236.

Specification of Letters Patent. Patented Apr. 18, 1922.

Application filed October 11, 1920. Serial No. 416,312.

To all whom it may concern:

Be it known that I, JOHN H. OWENS, a citizen of the United States, and resident of Racine, in the county of Racine and State of

5 Wisconsin, have invented certain new and useful Improvements in Traps or Clean-Out Covers; and I do hereby declare that the following is a full, clear, and exact description thereof.

10 My invention refers to cap closures for plumbers' traps or clean-out covers, which are particularly adapted to be sunk into the floors of bathrooms or the like, the caps being in threaded union with the mouth of the 15 trap whereby they can be removed for various purposes.

In caps for traps of this general type the usual method of removing them is to provide such traps with projections, and these projections are a constant annoyance as they preclude the desirability of obtaining a flush floor and thus frequently cause individuals to stumble over the projections.

Other types of caps attempt to overcome 25 this objectionable feature by using countersunk recesses. These recesses are formed so as to avoid projections above the floor, but in this type of cap there is a liability of individuals catching the heel of their shoe or 30 other part of the foot into the recess, and furthermore such recesses form dirt traps. Hence they do not overcome all of the objectionable features of the projecting head, nor do they meet the demand for the flush drop 35 cover or cap.

My invention has for its object to provide a simple, economical and effective flush cap of the type mentioned, while at the same time provision is had for removing such flush 40 cap closure. The arrangement and construction of my invention, essentially embodies a polygonal recess in the upper face of the cap, and a complementary shaped plate adapted to fit within the recess to present a smooth 45 uninterrupted surface. Under normal conditions the plate is also provided upon its under surface with a projecting head for the reception of a suitable tool. Thus when it is desired to remove the cap, the plate is lifted from the recess and reinserted therein, with its head side projecting upwardly so as to provide means for receiving the tool, whereby the cover can be readily unscrewed from the body of the trap.

50 With the above objects in view, the invention consists in certain peculiarities of construction, combination and arrangement of parts as are hereinafter set forth with reference to the accompanying drawing and subsequent claim.

60 In the drawing:

Figure 1 represents a plan view of a cap embodying the features of my invention, the same being illustrated with a square plate fitted therein, having parts broken away and parts in section to show certain structural features.

Figure 2 represents a cross-section of the cap fitted to the mouth of a trap of any desired type, the complementary shaped plate 70 for the cover being shown in its normal position with the head thereof extending downwardly, whereby a flush upper surface is formed, the section being indicated by line 2-2 of Figure 1, and

75 Figure 3 is a similar sectional view of the device, showing the removable plate reversed and fitted into the squared recess preparatory to the cap being removed. In this position, the cap closure is to all intent and purpose, taken in connection with the removable plate similar to the standard cap in appearance.

80 Referring by character to the drawings 1 represents a cap closure having an annular threaded flange 2, which flange is adapted to enter the threaded mouth of a trap body 3, as best shown in Figure 2.

85 The central portion of the upper surface of the cap, is provided with a recess 4, the same being formed with rectangular side walls 5, and the central portion of this recess is countersunk to form a pocket 6. The pocket, in this instance, is shown with rectangular walls and said pocket is adapted to receive a squared head 7, which head projects from one face of a plug plate 8, having rectangular side edges that are adapted to fit snugly against the side edges of the recess 4 to thus form an uninterrupted surface, when the upper face 9 of the plate is exposed. 90 Hence it will be seen that the plug plate is provided with a smooth face, and from its opposite face there is extended a squared head 7, which is provided for the purpose of receiving a tool, whereby the cap closure 95 can be removed when desired.

100 As shown in Figure 3 of the drawing, the plug plate 8 has been reversed with relation to the cap recess 4, whereby the head 7 extends above the floor for the purpose of receiving the tool, and in Figure 2 of the draw-

ing, the plate is shown in its normal condition, in which it forms in connection with the adjacent surface of the cap, an uninterrupted face, whereby the recess in said cap 5 is closed and there is no liability of an accident, due to an individual coming in contact with the projection. As shown in Figure 1 in this instance I have provided a slight indenture 5' in one of the walls 5 of the rectangular shaped recess, for the purpose of inserting a blade or other instrument, whereby the loosely fitted plug plate can be readily lifted out of its seat.

While I have shown and described the cap 15 recess as being square and in nested engagement with a correspondingly squared plate, obviously the shape of the recess may be varied without departing from the spirit of the invention, as for example it may be six or 20 eight sided. It is also intended that the

screw threaded cap closure may be used in connection with any type of floor traps.

I claim:

A cap closure of the type described, having a polygonal shaped central recess in its 25 face, the same being formed with a head receiving pocket and a complementary plug plate adapted to be loosely fitted within the central recess, the plate having one uninterrupted smooth side and a tool receiving head 30 extending from its opposite side, the head being adapted to rest within the recess pocket when the smooth side of the plate is uppermost to thus form an uninterrupted cap surface.

In testimony that I claim the foregoing I have hereunto set my hand at Racine, in the county of Racine and State of Wisconsin.

JOHN H. OWENS.
